UNITED STATES PATENT OFFICE.

JOSEPH H. MORIN, OF NASHUA, NEW HAMPSHIRE.

STAMPING MACHINE.

Application filed February 27, 1922, Serial No. 539,667. Renewed February 12, 1925.

To all whom it may concern:

Be it known that I, JOSEPH H. MORIN, a citizen of the United States of America, residing at Nashua, in the county of Hillsborough and State of New Hampshire, have invented new and useful Improvements in Stamping Machines, of which the following is a specification.

This invention relates to numbering machines and more particularly to a type of machine adapted for hand operation to apply selective numbers to boxes, or any containers or other surfaces. Though not in all respects limited thereto the invention is 10 preferably and as herein shown embodied in a type of stamping machine wherein the numbers are borne by series of rubber bands which are adjustable to present the required combinations of numbers. One principal object of the invention is to provide a numbering machine of the type stated with an automatic counter or registering device adapted to register accurately the number of times that any given number has been stamped. A 15 further object is to provide a combination numbering and registering machine of the type set forth with a bell or like signal adapted to indicate by its ring each impression made by the stamping machine. A further object is to provide a numbering machine with a printing face equipped with fingers or feelers adapted when pressed against the surface to be printed, to cause the actuation of the registering counter and 20 also to operate the bell or like signal. A still further object is to provide improved means for adjusting the rubber bands which bear the numbers, the device for this purpose embodying also a locking clamp holding the numbers from movement while being 25 used. A still further object is to provide a numbering machine with a convenient compartment for holding a reserve stock of ink. A still further object is to provide a numbering machine of the type stated that is 30 economical of time and labor in use and capable of insuring both speed and accuracy without any particular skill on the part of the operator in using the same. The foregoing and other objects and advantages of 35 the invention will more fully appear from the following detailed description taken in connection with the accompanying drawings, and the distinctive features of novelty 40 will be pointed out in the appended claims.

Referring to the drawings:

Fig. 1 is a front view of a numbering machine embodying the invention with portions broken away;

Fig. 2 is an end view thereof;

Fig. 3 is a partial end view showing the ink pad in a different position;

Fig. 4 is a partial sectional view on a relatively enlarged scale on line 4-5 of Figure 1 looking in the direction of the upper arrow;

Fig. 5 is a similar partial section on line 4-5 of Figure 1 looking in the direction of the lower arrow;

Fig. 6 is a sectional detail illustrating the mechanism for operating the signal bell;

Fig. 7 is a fragmentary section on line 7-7 of Figure 1; and

Fig. 8 is a sectional detail on line 8-8 of Figure 1.

The housing and frame of the machine comprises side plates 10, 11 secured together at their tops by a tubular shell 12 which constitutes a hand piece and also serves as a chamber to hold a container or bottle B 80 of a reserve supply of ink. To permit access to this chamber one end thereof may be closed by a detachable plug 13 having a knurled head 13^a. The rubber bands which bear the numbers are illustratively shown as four in number with a designation 14. These bands are mounted at their upper portions upon rolls or drums 15, the surfaces of which may be suitably roughened to obtain a proper frictional hold upon the bands for turning the same. The lower portions of the bands pass around a plate 16 fixed to the bottoms of the side plates 10, 11. The drums 15 are rotatively mounted upon a shaft 17 which extends across the frame with its ends mounted in slots 18 of the plates 10, 11. As shown these slots are of a "keyhole" type with a relatively reduced upper portion 18^a in which the ends of the shaft 17 are normally received, the shaft ends having notches 90 engaging the sides of the slots to prevent endwise removal, while the lower portions of the slots are relatively enlarged as indicated at 18^b to permit removal of the shaft endwise when it is located in this part of the slots. For moving the shaft 17 upward in the slots 18 which results in drawing the bands 14 taut and preventing turning thereof, this shaft is engaged by the sides of horizontal slots 19^a in a swinging 100 105 110

frame 19 pivotally mounted at 20 in the side plates 10, 11. This swinging frame 19 is generally of a U-shape with its lower portion 19^b formed as a vertically extending plate with an inturned edge 21 adapted when the swinging frame is swung downward to render the bands taut, to engage therewith and further lock them against movement. The plate 19^b bears a knob or finger piece 22 by which the swinging frame may be swung outward on its pivots 20 resulting in lowering the slots 19^a and hence the shaft 17 to loosen the rubber bands and permit them to be turned. Suitable means may be provided for locking the swinging frame in its inward position with the bands held taut and against movement. For this purpose I show spring pressed pins 23 fitted in housings 24 borne by the side plates 10, 11, these pins being pressed into holes 25 of the swinging frame when said frame is swung inward as shown in Figure 2. These pins are equipped with compression springs 23^a enclosed in the housings 24 and have at their projecting ends finger pieces 23^b by which they may be drawn outward. For turning the drums 15, each of them bears a ratchet wheel 26 upon its hub portion and these ratchet wheels are engaged by spring pressed pawls 27 pivoted to lever plates 28 swingingly mounted upon the shaft 17. These plates are equipped with projecting finger pieces 28^a at the upper edges thereof and their lower edges are also formed with projections 28^b engageable with a shaft 29 borne by the frame which limits the downward or return movement of said levers. Thus by operating the finger pieces 28^a, any required combination of numbers may be presented in operative position, i. e. underneath the plate 16. 30 indicates a pad holder for an inking pad 30^a, which is mounted to swing into position for applying ink to the numbers after each operative movement. For this purpose the pad holder bears at its ends bent upturned arms 31. The upper ends of these arms are fixed to a shaft 32 which extends across the frame and has its end portions pivotally mounted in swinging bars 33 at the sides of the frame, the inner ends of these bars being fixed to the extremities of the shaft 29. An intermediate portion of the shaft 32 has fixed thereto short spaced apart arms 34, the outer extremities of which are pivotally engaged at 35 with the lower end of an upwardly extending bar 36. The shaft 32 has fixed thereto in proximity to the arms 34, a coil spring 37 having an upwardly extending projection 37^a with a small roll 37^b at its extremity which bears against the bar 36 some distance from its extremity, the action of this spring thus tending to swing the pad inward to operative position. The upper end of the bar 36 is pivoted at 38 to a depending portion 39^a of the lever 39 which is journalled on a shaft 40 extending across the upper portion of the frame. The lever 39 is formed with an outwardly projecting finger piece 41 which may be of substantial width, i. e. extending substantially across the frame so that all of the fingers of the hand may engage therewith. One important feature of the invention comprises means whereby a counter is operated and a signal, such as a bell actuated at each stamping impression made by the machine. For this purpose I provide spaced apart fingers or feelers 42 slidably mounted to extend in one position downward below the stamping plane, and being pressed backward when the impression is taken, this pressing backward of said fingers serving to actuate the counter and the bell. As herein shown the fingers 42 are united together by a plate 43 and they are slidably guided for vertical movement, having slots 44 in their upper ends which fit around a shaft 45 journalled in the slide plates. This feeler or finger-unit has secured thereto a bar 46 extending upwardly in the frame with its upper end pivotally engaged at 47 with a short lever arm 48 fixed to the shaft 40. This shaft 40 extends at opposite sides of the frame with its extension at one side having a counter device 49 associated therewith to be operated by a one-way movement of the shaft 40 to register the stamping operations. The other end portion of the shaft after extending through a sleeve bearing 50 within the frame, projects outward through the side plate 10 where it has fixed thereto an arm 51 bearing a pivoted pawl 52. This pawl on the reverse clockwise movement of the shaft 40, as seen in Figure 6, i. e. as the fingers 42 are being pressed inward, engages a shoulder 53 on a head 54 pivoted on a stub shaft 55 at the end of the frame. This head 54 bears an arm 56 with a bell hammer 57 at its outer end and it is acted on by a spring 58 mounted on the shaft 55 which normally tends to swing the hammer 57 into engagement with a bell 59. Thus the pawl 52 engaging the shoulder 53 draws the bell hammer inward as the fingers 42 are being pressed inward for a stamping operation, and as soon as such operation is completed, the pawl 52 passes the end of the shoulder 53 permitting the reaction of the spring 58 to sound the bell, while the pivotal mounting of the pawl 52 permits it to ride past the shoulder 53 on the return, or resetting movement of the fingers 42. This resetting movement of the fingers 42 is accomplished by a spring 60 mounted on a fixed shaft or bar 61 in the lower portion of the frame with projecting extremities 60^a, 60^b engaging in holes 42^a in the fingers 42. Suitable means is provided for holding the fingers 42 retracted after an operating movement until after the inking pad has been pressed upon 130

the stamping surface. For this purpose one of these fingers is provided with a small block 62 presenting a ledge or shoulder 62^a for co-operation with a part circular stop 5 or abutment member 63 formed upon the shaft 45. This abutment member 63 is cut away at one side thereof as indicated at 63^a at a point so that when the shaft 45 is oscillated as now to be described in withdrawing the inking pad from the stamping surface, this cut away portion will come opposite the ledge 62^a and permit the fingers to be pressed downward by the action of the spring 60. This oscillation of the shaft 45 is accomplished by means of a pivoted pawl 64 mounted on a head 65 borne by the shaft 29, this pawl engaging a ledge 66^a on a head 66 fixed to the shaft 45. The pawl 64 is adapted to move past the shoulder 66^a on 10 its operating movement, and after releasing the fingers 42 as described, the shaft 45 is returned or reset by means of a spring 67 engaging the same. For returning the parts including the inking pad and the hand piece 25 to normal position, i. e. with the stamping pad pressed upon the stamping surface, suitable spring means is provided, this being shown as a stout coil spring 68 mounted upon the shaft 29 with one end thereof fixedly 30 anchored as indicated at 68^a, and its other end engaging a short arm projecting from the shaft as indicated at 68^b. Thus at the beginning of an operating movement the user taking hold of the finger piece 41 draws 35 the inking pad 30^a away from the stamping surface, the fingers 42 being then projected beyond the stamping surface as shown in Figure 3. Then as the machine is pressed upon the material to stamp the desired impression, the fingers 42 will be pressed backward against the tension of the spring 60, this resulting in oscillating the shaft 40 through the link bar connection 46 until the completion of the operating movement, when 40 as the fingers are fully pressed inward, the pawl 52 moving past the ledge 53 will permit the bell to sound, while at the same time the other end of the shaft 40 actuates the counter. Thereupon the operator releasing 45 the piece 41, the inking pad is returned over the stamping surface by the spring 68, the fingers 42 being then held retracted by the engagement of the shoulder 62^a with the stub or abutment member 63. Upon starting 50 to draw back the inking pad the shaft 45 is oscillated as described to release the shoulder 62^a and permit the fingers to be again projected forward beyond the stamping surface. I am aware that the invention may be

embodied in other specific forms without departing from the spirit or essential attributes thereof, and I therefore desire the present embodiment to be considered in all respects as illustrative and not restrictive, reference being had to the appended claims 60 rather than to the foregoing description to indicate the scope of the invention. 65

Having described my invention, what I claim as new and desire to secure by Letters Patent is:

1. The combination with a machine for stamping numbers or the like having stamping elements, of registering and signal mechanism associated therewith having an operating element projecting normally beyond 70 the printing face and yieldable as the printing face is pressed upon a receiving surface, to actuate said registering and signal mechanism.

2. A numbering or like machine comprising adjustable bands presenting a printing face, registering and signal mechanism, fingers yieldably mounted and normally projecting outward from the printing face having a connection to actuate said registering 75 and signal mechanism as they are pressed inward by engagement with the receiving surface, and means for inking the printing face while said fingers are withdrawn.

3. A portable hand operated machine for numbering and like uses comprising a printing face, registering and signal mechanism, fingers yieldably projecting outward from the printing face and connected to actuate said registering and signal mechanism as 80 they are pressed inward, and an inking device having a manual connection to actuate the same with means associated therewith for resetting said fingers.

4. A stamping machine of the kind described comprising a plurality of flexible bands presenting a changeable printing face, individual ratchet devices for actuating each of said bands, and a swinging frame providing a mounting for one end portion of said bands adapted to be detachably secured in position for drawing the bands taut and locking the same against movement after adjustment thereof.

5. A stamping machine comprising a plurality of bands presenting a changeable printing face, a ratchet device for each of said bands to actuate the same, and a swinging mounting for the bands adjustable to loosen them for movement and to hold them 105 taut against movement for operation.

In testimony whereof I affix my signature.
JOSEPH H. MORIN.
